UNITED STATES PATENT OFFICE

JOSEPH H. COHEN, OF BRIDGEPORT, CONNECTICUT

DESIGN FOR A FENDER APRON

Application filed April 2, 1932. Serial No. 43,365. Term of patent 14 years.

To all whom it may concern:

Be it known that I, JOSEPH H. COHEN, a citizen of the United States, residing at Bridgeport, in the county of Fairfield and State of Connecticut, have invented a new, original, and ornamental Design for Fender Apron, of which the following is a specification, reference being had to the accompanying drawing, forming part thereof.

The figure is a perspective view of the obverse side of the fender apron, showing my new design.

The reverse side of the fender apron, not shown, is substantially plain and unornamented.

I claim:

The ornamental design for a fender apron, as shown and described.

JOSEPH H. COHEN.
